P. GROEBER.

WALL AND CEILING COVERING.

No.19,617.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,617, dated January 28, 1890.

Application filed December 26, 1889. Serial No. 335,048. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design consists of a section of a square having an inner circle, four of which are required to form the complete square and circle. The combined and complete figure has a central rosette 1,

15 from which pointed leaves form the outer circle. From the point of each leaf rises a

staff 2, having a pointed ornament at its apex. All the staves are connected by a fringe or border 3. The circle is further ornamented with festoons of flowers 4. There 20 are four corner ornaments of scrolls 5 and an outer border 6 of beads and fluted ornaments.

What I claim is—

The design for a wall and ceiling covering herein shown and described, consisting of a 25 circle ornamented with festoons, bands, and staves around a central rosette, and four corner ornaments and borders, forming a square.

PAUL GROEBER.
